2 Sheets-Sheet 2

Fig-2-

This technical drawing illustrates a vertical assembly, likely a component of a larger machine or structure. The assembly consists of several vertical and diagonal elements, some of which are hatched to indicate different materials or sections. Key components labeled include:

- 1: Top horizontal plate or cap.
- 2: Vertical support or frame.
- 3: A small rectangular component attached to the frame.
- 4: A horizontal plate or cap, possibly a cover or lid.
- 5: A vertical plate or support element.
- 6: A vertical plate or support element.
- 7: A vertical plate or support element.
- 8: A vertical plate or support element.
- 9: A vertical plate or support element.
- 10: A vertical plate or support element.
- 11: A vertical plate or support element.
- 12: A vertical plate or support element.
- 13: A vertical plate or support element.
- 14: A base or foundation plate.
- 15: A vertical plate or support element.
- 16: A diagonal plate or support element.
- 17: A horizontal plate or cap.
- 18: A horizontal plate or cap.
- 19: A horizontal plate or cap.
- 20: A base or foundation plate.
- 21: A base or foundation plate.
- 22: A base or foundation plate.

The drawing uses a combination of solid lines for structural elements and dashed lines for internal or less prominent features. Hatching is used to distinguish between different parts, such as the base plates (14, 19, 20, 21, 22) which are consistently hatched, while the vertical supports (1-13) are not.

WITNESS:

UNITED STATES PATENT OFFICE

AARON F. CORE, OF PIERRE, SOUTH DAKOTA

WINDOW SET

Application filed July 26, 1932. Serial No. 624,844.

This invention relates to window sets and more particularly to the mounting of storm sashes or window screens and has for the primary object, the provision of a device of the above stated character, whereby a storm sash or screen may be easily and quickly installed or removed from the inside of a window frame and when applied is so connected to the upper sash of the window that the opening or closing of said storm sash or screen will impart sliding movement to the upper sash for opening and closing the latter.

Another object of this invention is the provision of an operating means between the storm sash or screen and the window frame and the upper sash thereof for causing an outward and downward movement of the storm sash or screen when opening pressure is applied thereto without the upper end of the latter moving outwardly of the window frame and simultaneously causing a sliding movement of the upper window sash downwardly to provide ventilation and allowing the lower sash of the window to be opened and closed as usual.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a rear elevation partly in section illustrating a window sash constructed in accordance with my invention.

Figure 2 is a sectional view taken on the line 2—2 of Figure 1, illustrating a storm sash or window screen in a closed position.

Figure 3 is a similar view showing the storm sash or screen in an opened position.

Figure 4 is a detail sectional view taken on the line 4—4 of Figure 1.

Figure 5 is a fragmentary perspective view showing the means of slidably connecting the storm sash or screen to the window frame.

Figure 6 is a detail view partly in section illustrating the connection between the operating medium and the window frame.

Figure 7 is a detail sectional view taken on the line 7—7 of Figure 6.

Referring in detail to the drawings, the numeral 1 indicates a window frame having 55
slidable upper and lower window sashes 2 and 3, both of which are balanced by weights 4. Guides or tracks 4' are secured to the upper portion of the window frame 1 and are arranged vertically with their upper ends curved inwardly relative to the window frame 60 as shown at 5. The lower portions of the guides or tracks 4' are engaged by pivotally mounted stops 6. The tracks 4' and stops 6 are carried by attaching plates 7 secured to the sides of the window frame by screws or 65 like fasteners 8.

A storm sash or screen frame 9 extends the full length and width of the frame 1 and has secured adjacent its upper edge brackets 10 engageable with the tracks 4' and when said 70 brackets engage with the curved portions 5 of the tracks they cause an inward movement of the sash or screen frame 9 relative to the window frame 1 thereby establishing a tight fit therebetween. The lower portion of the 75 frame 9 carries a plate 11 to which is pivoted a button 12 engageable with a keeper 13 secured to the sill 14 of the frame for locking the frame 9 in the window frame 1.

Brackets 15 are secured to the lower run 80 of the upper sash 2 and have pivotally and detachably connected thereto the upper ends of operating arms or rods 16. The rods or arms 16 are pivotally connected to elements 17 fixed to the frame 9 which also have pivoted thereto braces 18 carrying pivots 19 operable in key hole slots 20 of channel iron plates 21 secured to the frame 1 by screws or 85 like fasteners 22.

In operation when the device is positioned 90 as shown in Figure 2, the button 12 is released from the keeper 13 and outward pressure is exerted on the lower portion or edge of the frame 9 causing the latter to slide downwardly and outwardly into a position as shown in Figure 3, simultaneously sliding the upper sash 2 downwardly for the purpose of giving ventilation through the window frame 1. The downward and outward movement of the frame 9 being limited by the stops 6. When 100

the frame 9 is returned to a closed position as shown in Figure 2, the sash 2 is slid upwardly into a closed position. To remove the frame 9 from the frame 1, the stops 6 are moved out 5 of engagement with the tracks 4' and the pivots 19 are removed from the key hole slots of the plates 21 and the arms 16 are detached from the brackets 15, thus permitting complete detachment of the frame 9 from the 10 frame 1 when the brackets 10 disengage from the tracks.

The device 9 may be in the form of a window screen or a storm sash or may be a closure for a store window or the like wherein it is 15 sometimes desirous to remove the same for the purpose of conducting business and the like.

The storm sash or screen being connected to the usual counter-balanced upper sash of 20 the window will provide a construction which will maintain the storm sash or screen at any of its positions after being manually moved into a position with freedom during its movement.

25 While I have shown and described the preferred embodiment of my invention, it will be understood that minor changes in construction, combination and arrangement of parts may be made without departing from 30 the spirit and scope of my invention, as claimed.

Having thus described my invention, what I claim is:—

35 1. In combination with a window frame having slideable upper and lower sashes, an auxiliary frame carried by the window frame, means for closing said auxiliary frame to form either a screen or a storm sash, means for slidably and detachably connecting the 40 upper end of the auxiliary frame to the window frame, and an operating means between the upper sash, window frame and the auxiliary frame to cause opening and closing of the 45 upper sash by the opening and closing of the auxiliary frame.

50 2. In combination with a window frame having slideable upper and lower sashes, an auxiliary frame carried by the window frame, means for closing the auxiliary frame, tracks 55 carried by the window frame, brackets secured to the upper portion of the auxiliary frame and engageable with the tracks, and an operating means between the upper sash and the auxiliary frame and the window frame.

60 3. In combination with a window frame having slideable upper and lower sashes, an auxiliary frame carried by the window frame, means for closing the auxiliary frame, tracks 65 carried by the window frame, brackets secured to the upper portion of the auxiliary frame and engageable with the tracks, an operating means between the upper sash and the auxiliary frame and the window frame, and pivotal stops carried by the tracks to be

engaged by the brackets for limiting the opening movement of the auxiliary frame.

4. In combination with a window frame having slideable upper and lower sashes, an auxiliary frame mounted in said window frame, means for closing the auxiliary frame, guide tracks on the window frame, means carried by the auxiliary frame to slidably engage the tracks, operating arms detachably and pivotally connected to the upper sash and pivotally connected to the auxiliary frame, braces pivoted to the auxiliary frame and pivotally and detachably connected to the window frame to cause simultaneous opening and closing of the auxiliary frame and the upper sash with each other.

In testimony whereof I affix my signature,
AARON F. CORE.
